Primary Examiner — Elizabeth Albert*(74) Attorney, Agent, or Firm* — Veal Intellectual Property, LLC(57) **CLAIM**

The ornamental design for a indicia fields, as shown and described.

DESCRIPTION

FIG. 1 is a perspective view of indicia fields showing my new design;

FIG. 2 is an inverted perspective view thereof;

FIG. 3 front view thereof;

FIG. 4 is a rear view thereof;

FIG. 5 is a right side view thereof;

FIG. 6 is a left side view thereof; and,

FIG. 7 is a top view thereof.

The broken lines are included for the purpose of illustrating portions of the writing instrument and indicia that form no part of the claimed design.

1 Claim, 4 Drawing Sheets(56)
